LOADING MACHINE.

1,415,485.

Specification of Letters Patent.

Patented May 9, 1922.

Application filed March 29, 1921. Serial No. 456,724.

To all whom it may concern:

Be it known that I, WILLIAM SCHLUTER, Jr., a citizen of the United States of America, and resident of Bellaire, county of Belmont, and State of Ohio, have invented certain new and useful Improvements in Loading Machines, of which the following is a specification.

This invention relates broadly to loading apparatus, and more specifically to a power-driven scoop and conveyor for loading materials in cars or the like.

The primary object of the invention is to provide an apparatus or machine whereby coal or other loose materials may be rapidly and economically handled in loading cars for transportation, and which is especially adapted for use in mines and other places affording limited overhead space.

A further object is to provide a power-driven machine of the character mentioned which embodies traction means whereby it may be propelled forward and back without the use of trackways and whereby it may be readily shifted as required to present the scoop thereof at any desired angle to the material acted upon.

A still further object is to provide an efficient and practical shovel or scoop which requires a minimum of space in its operation.

With these and other important objects in view, the invention resides in the features of construction, arrangement of parts and combinations of elements which will hereinafter be fully described, reference being had to the accompanying drawings, in which—

Figure 1 is a side elevation of the invention, showing the scoop in the position occupied at the end of its advance stroke;

Figure 2 is a similar view of the front end of the machine with the scoop thereof occupying dumping position;

Figure 3 is a similar view, showing the scoop in retracted position;

Figure 4 is a view in top plan with a portion of the conveyor broken away;

Figure 5 is a section taken substantially on line 5—5, Fig. 1, illustrating the means for driving the conveyor;

Figure 6 is an enlarged top plan view of the automatic clutch-shifting mechanism for effecting intermittent actuation of the scoop.

Figure 7 is a sectional elevation taken substantially on line 7—7, Fig. 6;

Figure 8 is a sectional elevation of the driving means whereby the scoop actuating levers are driven, showing the gearing for reversing the tractor; and—

Figure 9 is a sectional elevation on line 9—9, Fig. 8.

Referring to said drawings, in which like designating characters distinguish like parts throughout the several views—

1 indicates the endless traveling treads of a tractor of the caterpillar type, the same being carried by wheels 2 mounted on axles 3 and 4. Suitably carried by said axles is a frame which comprises parallel side members 5 having a platform 6 mounted on the rear end thereof. An electric motor 7 mounted on said platform or other suitable mounting has a worm 8 mounted on its shaft 9 and disposed in operative relation with the worm gear 10 loosely mounted on a transverse shaft 11 carried in bearings 12 supported by said frame. A shiftable clutch 13 carried by said shaft is movable into and out of engagement with said worm gear for operatively connecting said shaft to said gear. Also loosely mounted on said shaft 11 is a pinion 14 which is permanently disposed in mesh with a gear 15 fixed on a shaft 16 located parallel to and rearward of said shaft 11, said shaft 16 being journaled in bearings 17 suitably mounted upon the frame or the platform.

Carried upon the outer ends of the shaft 16 are crank arms 18 each of which has a wrist pin 19 connected by a pitman 20 to a similar pin 21 carried by a member or slide 22 which is slidably mounted upon the adjacent side member 5 of the frame, said crank arms and said pitmen being adapted, when said shaft 16 is rotated, to impart reciprocating sliding movements to said slides.

Mounted upon a pivot pin 23 carried by each of the slides 22 is the rear end of a lever 24 constituting a support upon which is carried a shovel or scoop 25 designed for taking up loose or incoherent material, as coal, and delivering the same to an inclined conveyor which comprises an endless traveling belt or apron 26. Said apron comprises transverse slats carried by sprocket chains 27 carried by sprocket wheels 27' and 28' located respectively at the front and rear

- ends of the machine, said wheels 27' having the shaft 28 by which they are carried journaled in bearings 29 supported by the frame on a suitable low-level, while the wheels 28' 5 are elevated to an appropriate height for supporting the parts of the conveyor above and in non-interfering relation to the drive-gearing of the machine. As herein shown, the wheels 28' are carried in substantially 10 upright side members or guards 30 located laterally of the apron 26, and said guards are in turn supported on the upright arms 31' carried on the ends of a transverse bar 31 which surmounts a vertical threaded sup- 15 porting stem 32. Said stem is threaded through the hub of a hand wheel 33 which rests upon a bar 34 carried by standards 35 rising from the frame of the machine. As is obvious, adjustment of the elevation of the 20 rear end of the conveyor is effected by rotation of the adjusting wheel 33. Motion is communicated to the apron 26 by a chain 79 connecting sprocket wheels 80 and 81 carried respectively by shafts 11 and 28. 25 Suitably carried by the front end of the frame is a stationary forwardly-facing guard-like plate 36 which extends from the upper edge of the front end of the conveyor enclosure approximately to the ground level 30 and which has a width closely approximating the internal width of the scoop. Said plate or guard 36 constitutes, in effect, a back for the scoop, which latter is open at its rear end as well as at its front end. 35 The scoop is operable from its farthest retracted position, shown in Fig. 3, to its most advanced position, shown in Fig. 1, for taking up a load of the material acted upon, and is thence elevated to the inclined position 40 shown in Fig. 2, in which its load is delivered by gravity through the open rear end thereof to the front end of the conveyor. As the scoop is thus elevated, the guard 36 retains the material in the scoop, or prevents 45 the material from passing out through the open rear end of the scoop.

As hereinbefore indicated, the slides 22 are actuated to reciprocate, motion being communicated thereto by rotation of the shaft 16 50 through the intermediacy of the crank-arms 18 and pitmen 20. Obviously, therefore, the scoop 25, which is connected to said slides through the levers 24, is also reciprocated, the opposite limits of the reciprocation being 55 shown in Figs. 1 and 3.

The elevation of the scoop from the advanced position shown in Fig. 1 is effected following its forward thrust to said position by means of mechanism which swings the 60 scoop-carrying levers or arms 24 upward with the pivot pins 23 serving as fulcrums. Said mechanism includes pitmen 37 which have their rear ends mounted on wrist pins 38 carried by crank arms 39 fixed on opposite ends of the shaft 11. When the machine

is in operation said shaft 11 is continuously driven; hence, the pitmen 37 are continuously actuated, but, as will hereinafter be explained, this actuation is without effect except when the scoop is at the limit of its 70 forward thrust in position to be elevated.

Carried by the shaft 11 is a clutch 40 which is shiftable into and out of driving engagement with the pinion 14 which, as hereinbefore stated, is loosely carried by 75 said shaft. Said clutch 40 is associated with mechanism whereby it is shifted out of engagement with said pinion at the end of each revolution of said shaft and then is re-engaged with said pinion at the end of the 80 next succeeding revolution, the purpose being to actuate rotation of the shaft 16 only at alternate revolutions of the shaft 11. Since the circumference of the gear 15 is just double that of said pinion 14, it is apparent that but one-half a revolution is imparted to the shaft 16 at each actuation thereof. Thus, at one actuation, the shaft 16 advances the scoop from its rearmost to its foremost position, as for taking up a 90 load, then remains stationary during a complete revolution of the shaft 11, during which time the scoop is elevated to and returned from its dumping position, as will hereinafter be explained, and then at the 95 next actuation retracts the scoop to its initial position in which it underlies the front end of the frame, such retraction being permitted since the scoop has no rear end closure and the sides of the scoop are arranged 100 to straddle the frame.

The means or mechanism by which the clutch 40 is shifted into and out of operative relation to the pinion 14, as aforesaid, at regular intervals comprises a gear wheel 105 41 fixed on the shaft 11 in mesh with a similar gear 42 fixed on a countershaft 43 journaled in bearings 44 carried by the platform 6. A disk 45 carried by said countershaft presents a cam face 46 which, in the rotation of the cam, is traversed by a roller 47 carried by a side of a shifter arm 48 that has one end pivotally mounted, as on a stationary lug 49, and its opposite end operatively associated with said clutch. A compression spring 50 interposed between said arm and an adjacent stationary lug 44' 110 yieldingly maintains said arm in its outwardly thrust position. It will thus be apparent that, during the time that the roller 115 47 travels over the highest surface presented by the face of the disk 45, the clutch will be held out of engagement with the pinion against the tension of the spring 50; and that, as the roller 50 drops to the lower surface of said disk, the clutch will interengage with said pinion. 120

The pitmen 37 which form parts of the mechanism for swinging the scoop to and from dumping position, as aforesaid, have 130

their front ends pivotally attached to the upper ends of blade-like rockers 51 which are pivotally mounted intermediate their ends upon the side members 5 of the frame 5 at an appropriate point. Each rocker 51 carries upon its outer face a roller 52 which, when the slides 22 reach their farthest advanced positions, is contacted by the upper rear edge of a substantially upright blade 10 53 carried by, or formed integral with, the rear end of the adjacent scoop-carrying arm 24. Then, upon rearward reciprocating movement of the pitman 37, which acts to swing the upper end of said rocker 51 rearward, a force is exerted through the said 15 roller 52 acting upon the front edge of said blade which impels the arm 24 to swing upon its pivotal mounting to the position shown in Fig. 2. A roller 54 is carried on the inner face of the lower portion of the arm 24 which also travels in engagement with the rear edge of the lower end of said rocker 51. With the return, or forward, thrust of the pitmen 37 the scoop-carrying 20 arms 24 are lowered to their normal positions. Immediately following such return of the scoop supporting arms, the same are drawn rearward in the manner hereinbefore explained for returning the scoop to initial 25 position.

As shown, the arms 24 are mounted upon trunnions 55 formed on the sides of the scoop, and having brackets 56 disposed for furnishing additional support thereto. Said 30 arms have upwardly and forwardly inclined front end extensions 24' provided with open seats 57 in which, when the scoop occupies its normal horizontal position, are received laterally extending arms or trunnions 58 carried by the sides of the scoop. Due to the recited manner of attaching the arms 24 to the scoop, the latter is free to tip up to an inclined position, as when, in returning from its elevated dumping position, its front 35 end seats upon a ground elevation or underlying material which prevents its assuming horizontal position. This construction also enables the scoop to be advanced over rough or uneven surfaces in a manner which would be impossible if a rigid connection were provided between the scoop and its supporting arms.

Power for driving the tractor is transmitted, first, from the shaft 11 to a suitably located 40 countershaft 59, as by means of a sprocket chain 60 passed over sprocket wheels 61 and 62 carried by said shafts, said sprocket wheel 62 being loosely carried by said countershaft and being adapted to be operatively 45 connected with the latter through the intermediacy of a shiftable clutch 63. Said countershaft 59 carries a drive gear 64 which is straddled by a yoke 65 that has its parallel members loosely mounted on said counter- 50 shaft. Carried between the lower or depend-

ing ends of said yoke members are two smaller intermeshing gears 66 and 67 of which the former is permanently in mesh with said gear 64. Said yoke has attached thereto a hand lever or rod 68 by means of 55 which it may be swung on said countershaft 69 to dispose either of said gears 66 or 67 into operative engagement with a gear 71 which is fixed on a shaft 70 for driving the latter, the direction of rotation of said shaft 75 70 being dependent upon which of said gears 66 or 67 assumes operation relation to its said gear 71.

Mounted on said shaft 70 is a sprocket wheel 69 which is connected by a chain 72 80 to a similar sprocket 73 fixed upon a sleeve 74 which is rotatable upon the rear axle 4 of the tractor and which is journaled in bearings 75 formed on a bracket 76 depending from the platform or other suitable 85 frame member. The opposite ends of said sleeve are dentated for interengagement with two opposite clutch members 77 and 78 either or both of which is shiftable on said axle with respect to said sleeve. Each 90 of said clutch members is so related to the adjacent wheel 2 of said axle that the latter is actuated to rotate therewith.

It will thus be understood that when it is desired to advance the tractor, the clutch 95 63 is shifted into operative relation to the sprocket wheel 62, and the rod 68 is thrust forward to present the gear 66 into like relation to the gear 71. Then, with both of the clutches 77 and 78 in operative relation 100 to the sleeve 74, both tractor treads 1 will be actuated to travel forward. When, on the other hand, it is desired to turn the machine, or to shift the same around so that it will present the shovel at a different angle to the 105 work, but one of said sleeve-engaging clutches may be shifted into operative position, in which case the driven tractor tread will impel the machine to turn in a minimum of turning space.

When it is desired to cause the tractor to reverse, or travel rearward, the rod 68 is drawn rearward to dispose the gear 67 in operative relation to the gear 71 for actuating the last mentioned gear rearward.

Suitable levers, as 82 and 83, are provided whereby the clutches 77 and 78, may be shifted.

It will be noted that the frame of the machine is supported on the rear axle 4 by 120 means of suitable bearings 84, while it is wholly dissociated from the front axle 3. A transverse shaft 85 mounted in opposite channel bar members 86 which connect said axles carries cams 87 having their faces in 125 underlying supporting relation to the sides 5 of the machine frame. By rotary movement of said shaft 85, effected in any appropriate manner, as by means of a hand lever 88 on the end of said shaft, the elevation 130

of the front end of said machine frame may be adjusted either to present the front end of the machine, including the scoop, on its proper operating level or to hold said front end, with the scoop, sufficiently elevated to permit of unhindered travel of the machine, as when it is desired to move the latter from one place to another. In such adjustment, the rear axle 4 serves as a fulcrum upon 10 which the frame swings as on a hinge or pivot.

What is claimed is—

1. A loading machine comprising a tractor, a frame carried thereby, slides mounted 15 on said frame, means for reciprocating said slides, arms pivoted to said slides, a scoop pivotally connected to said arms, and means acting upon said arms at the limit of the forward movement of the scoop for elevating said arms to scoop dumping position.
2. A loading machine comprising a scoop, supporting arms connected to said scoop, means for reciprocating said arms, and means for actuating said arms to and from 25 elevated scoop-dumping position at the end of each forward stroke of said reciprocating means, the latter remaining inactive during operation of said elevating means.
3. A loading machine comprising a scoop, 30 means for reciprocating said scoop, a conveyor having its front end in overhanging relation to said scoop when the latter occupies its retracted position, and means operating at the limit of the forward thrust 35 of said scoop to actuate the latter to and from elevated dumping relation to said conveyor, said reciprocating means remaining inactive during operation of said scoop to and from dumping position.
4. A loading machine comprising a scoop, 40 means for intermittently imparting complete reciprocating movements to said scoop, a conveyor having its front end located in overhanging relation to said scoop when 45 the latter occupies its retracted position, and means operating at the limit of the forward thrust of said scoop to actuate the latter to and from elevated dumping relation to said conveyor.
5. A loading machine comprising a frame, 50 a conveyor superposed over said frame, a scoop having its opposite ends open, intermittently reciprocating means carried by said frame for retracting and advancing 55 said scoop, means operating at the limit of the forward thrust of said scoop to actuate the latter to and from elevated dumping relation to said conveyor, and a guard arranged to cooperate with the open rear end 60 of said scoop for retaining material in the latter until dumping position is assumed.
6. A loading machine comprising a frame, 65 a conveyor superposed over said frame, a scoop having its opposite ends open, supporting arms attached to said scoop, inter- 70 mittently reciprocating means connected to said arms whereby the latter are actuated to retract and advance said scoop in an approximately horizontal plane, a stationary guard plate which is straddled by said scoop during reciprocation of the latter, and means operating in the interval between reciprocations to actuate said scoop to and from dumping relation to said conveyor, 75 said guard being located to cooperate with the open rear end of said scoop for retaining material in the latter during the elevating movement until dumping position is assumed.
7. A loading machine comprising a frame, 80 a conveyor superposed over said frame, a scoop having its opposite ends open, supporting arms attached to said scoop, intermittently reciprocating means connected to said arms whereby the latter are actuated to 85 retract and advance said scoop in an approximately horizontal plane, and means operating in the interval between reciprocations to swing said arms for elevating and lowering said scoop, respectively, to and from dumping relation to said conveyor, 90 and stationary means disposed to close the rear end of said scoop during elevating movement of the latter.
8. A loading machine comprising a frame, 95 a conveyor superposed over said frame, a scoop having its opposite ends open, supporting arms attached to said scoop, intermittently reciprocating means connected to said arms whereby the latter are actuated 100 to retract and advance said scoop in an approximately horizontal plane, a stationary guard plate which is straddled by said scoop during reciprocation of the latter, and means engageable with said arms whereby the latter are actuated in the interval between reciprocations to move said scoop to and from dumping position with respect to said conveyor, 105 said guard cooperating with said scoop during elevation of the latter for retaining material therein.
9. A loading machine comprising a frame, a constantly rotated shaft carried by said frame, a countershaft, intermeshing gears carried by said shafts, one of said gears being loosely mounted, a clutch for operatively connecting said gear to its shaft, automatic means for shifting said clutch at the end of each revolution of its shaft and whereby said gears are actuated at alternate 110 revolutions to effect rotation of said countershaft, a scoop, means intermediate said countershaft and said scoop whereby a complete reciprocation is imparted to the latter with each revolution of the former, and means reciprocated by said constantly rotated shaft whereby said scoop is actuated to and from elevated dumping position during the interval between reciprocations of the scoop.

10. A loading machine comprising a frame, a constantly rotated shaft carried by said frame, a countershaft, intermeshing gears carried by said shafts, one of said 5 gears being loosely mounted, a clutch for operatively connecting said gear to its shaft, automatic means for shifting said clutch at the end of each revolution of its shaft and whereby said gears are actuated at alternate 10 revolutions to effect rotation of said countershaft, a scoop, arms carrying said scoop, means intermediate said countershaft and said arms whereby the latter are reciprocated for retracting and advancing said 15 scoop at each revolution of the former, and means reciprocated by said constantly rotated shaft and adapted to coact with said arms whereby the latter are actuated dur- ing the interval between reciprocations thereof to swing said scoop to and from ele- 20 vated dumping position.
11. A loading machine comprising a cater- 25 pillar tractor, a frame superposed thereon, a scoop, intermittently actuated means for reciprocating said scoop, a conveyor mount- ed on said frame, and constantly reciprocating means arranged to actuate said scoop to and from dumping relation to said conveyor during the interval between reciprocations of said scoop.

30 In testimony whereof, I affix my signature in presence of two subscribing witnesses.
